UNITED STATES PATENT OFFICE.

EDWARD ALFRED KNIGHT AND ROBERT HAROLD FOLKES, OF LONDON, ENGLAND, AS
SIGNORS TO D. & W. GIBBS LIMITED, OF LONDON, ENGLAND.

METAL BOX.

Application filed June 18, 1928, Serial No. 286,188, and in Great Britain August 10, 1927.

This invention has reference to metal boxes or containers whereof the body is provided with a lever which is adapted by raising or other similar manipulation, to engage and 5 operate the lid so as to lift or release the same from the box body.

The present invention has for its object to provide an improved construction and arrangement of such a metal box or container 10 whereby the operation of lifting or releasing the lid is greatly facilitated and an economy in the cost of production effected.

According to this invention, the lever is hung upon a thin or shallow portion of the 15 rim of the box body formed by slotting the metal beneath the edge or bead of the rim circumferentially for a suitable distance; the said portion being pressed inward or otherwise worked so as to assume a rebated or 20 recessed position in relation to the general contour of the rim. The lever is constituted by suitably shaping or bending a strip of metal whereby a curled or tubular portion is provided for embracing the before-mentioned 25 thin or shallow rebated portion of the rim, the remaining portion of the strip being bent to a somewhat obtuse angle, in side view, so that, in the inoperative and closed position 30 of the box, it will meet and pass over the lower edge of the slot and enable the end which projects beyond the said edge to lie snugly against the outer face of the box body.

In order that the invention may be readily understood and carried into effect, same 35 will now be more fully described with reference to the accompanying drawings, in which:—

Figure 1 is an elevation and partial section of a lid and a box body having a lid lifting device according to the invention.

Figure 2 is a view in elevation showing the lid in position on the box body and the manner in which the projecting portion of the lever lies snugly against the outer face of the 45 box body.

Figure 3 is an elevation of the box body showing the thin or shallow portion formed by slotting the metal of the box body circumferentially thereof.

Figure 4 is a view partly in section and partly in elevation showing the pressed-in or rebated relationship of the said thin or

shallow portion to the general contour of the box body rim.

Figure 5 is a plan corresponding with Figure 3.

Figures 6 and 7 are a side and a face view respectively of the lever detached.

Figure 8 is a view of a box showing the improved device in operation.

a indicates the box body and *b* the lid. *c* is the thin or shallow portion of the rim of the box body which is produced by circumferentially slotting the metal of the side wall beneath the rim edge or bead, as at *d*, 65 the slot being of a depth adapted to permit the lever *e*, hereinafter described, to emerge from beneath the edge of the depending rim or skirt part of the lid *b*.

The said portion *c* is caused to assume a 70 rebated or recessed position in relation to the general contour of the rim of the box body (Figures 1, 4, 5) by pressing the same inward or by other convenient means.

The lever *e*, see Figures 6 and 7 particularly, is formed from a strip of metal whereof one end is so shaped or bent as to provide a curled or tubular portion *e*¹ in which the aforesaid thin or shallow portion *c* of the rim of the box body *a* resides and so serves as the 80 pivot or hinge pin for the lever when the latter is turned for the purpose of operating the same in lifting the lid. The part of the strip which extends from the said tubular portion *e*¹ is bent into an obtuse angle, as at 85 *e*² at which point it meets and passes over the lower edge of the slot *d* (see Figure 1) and the part *e*³ which extends beyond the said angle and the edge of the depending rim or skirt of the lid *b* lies snugly against the outer 90 face of the box body *a*.

In Figure 8, the box is shown with the lid *b* in closed position on the box body *a* and the projecting end *e*³ of the lever *e* lying snugly against the box body. In dotted lines, 95 the lever is shown in the position it assumes after being turned about the part *c* of the box body rim, in the act of lifting or releasing the lid, and the latter is indicated, also in dotted lines, in the lifted or released position.

It will be understood that by simply engaging the protruding end *e*³ of the lever by the finger or thumb and imparting an upward

movement thereto the lifting or removal of the lid may be effected.

If desired, the aforesaid protruding end of the lever may be arranged to project below the box bottom.

Owing to the free mounting of the lever on the part *c* of the box body rim, the manipulation thereof is rendered easy of accomplishment, the outer projecting end *e*³ being readily engaged by the finger or thumb nail and moved upwards thereby, such movement having a ready effect on the lid and resulting in its expeditious removal.

We claim:—

15. 1. In a metal box or container having a lever adapted for use in raising the lid, a box body of which the rim is formed with a thin shallow rebated portion obtained by slotting the side wall of the said body beneath the 20 rim edge in the direction of the circumference and a lever having a tubular part embracing the said shallow rebated portion and a tail part depending from the tubular part and emerging through the slot beneath the 25 said shallow rebated portion past the edge of the depending skirt part of the lid and lying snugly against the outer face of the box body.
2. In a metal box or container having a lever adapted for use in raising the lid, a box 30 body of which the rim is formed with a thin shallow rebated portion obtained by slotting the side wall of the said body beneath

the rim edge in the direction of the circumference and a lever having a tubular part embracing the said shallow rebated portion 35 and a tail part extending and depending from the tubular part and bent into an obtuse angle, at which angle it meets and passes over the lower edge of the circumferential slot in the rim of the box body and the tail part of the 40 lever which extends beyond the said angle lying snugly against the face of the box body and furnishing a grip for operating the lever in raising the lid.

3. In a metal box or container having a 45 lever adapted for use in raising the lid, the combination with a box body of which the rim is formed with a thin shallow rebated portion obtained by slotting the side wall of the said body beneath the rim edge in the direction of the circumference, of a lever constituted by a strip of metal which has a portion at one end bent to produce a tubular part for embracing the said shallow rebated portion of the box body rim and the remainder 50 bent into an obtuse angle so as to extend from the tubular part through the circumferential slot and at the aforesaid angle take a bearing on the box body and lie snugly against the outer face of the box body.

In testimony whereof we have subscribed our signatures this 29th day of May, 1928.

EDWARD ALFRED KNIGHT.
ROBERT HAROLD FOLKES.
